UNITED STATES PATENT OFFICE.

CHARLES WILLIAM DUNKELBURGER, OF CLINTON, IOWA, ASSIGNOR TO HEMINGWAY FURNITURE COMPANY, OF CLINTON, IOWA.

FOLDING TABLE.

1,058,417.

Specification of Letters Patent.

Patented Apr. 8, 1913.

Application filed May 11, 1911. Serial No. 626,519.

To all whom it may concern:

Be it known that I, CHARLES WILLIAM DUNKELBURGER, a citizen of the United States, residing at Clinton, in the county of Clinton and State of Iowa, have invented 5 a new and useful Folding Table, of which the following is a specification.

The object of my invention is to provide a folding table in which the supporting legs 10 are so interconnected that they simultaneously fold under the table top by a single operation. One pair of legs is pivotally connected to the table top near one end thereof, and the other pair of legs has a 15 combined sliding and pivotal connection with the table top. The two pairs of legs are so connected together by means of links that when the upper ends of the slidable legs are slid forwardly these legs fold 20 under the table top and at the same time the other pair of legs is automatically swung into folded position. When the legs are in folded position they rest against the under side of the table top, so that the folded table 25 occupies a minimum amount of space.

In the accompanying drawings Figure 1 is a perspective view of a folding table embodying my invention, the table being shown tilted back so as to expose the surface of the 30 table top where the legs are connected; Fig. 2 is a bottom plan view of the table showing the legs in folded position; and Fig. 3 is a cross-sectional detailed view showing one of the plates at the upper end of the slidable 35 legs in the undercut groove of the table top.

The top or body 1 of the table may be of any suitable form and is, for the sake of illustration, shown herein as the top of an ironing table. On the under surface of the 40 table near one end thereof is secured the transverse bar 2 by means of bolts or rivets 3, or in any other suitable manner. By providing the bar 2 with slots 3a through which the bolts extend, the top is free to shrink or 45 swell without danger of distortion. The bar 2 is preferably of metal and is at its ends provided with downwardly bearing flanges 4 for receiving the pivot pins 5 to which are pivoted the legs 6. A bracing board or strip 50 7 connects the legs 6 together. At the other end of the table 1 in the under surface thereof, is a pair of undercut grooves 8 which extend parallel and terminate at the point 9 which is at a suitable distance from the 55 total connection of the legs 6. The shape of

the grooves 8 is best shown in the detailed view of Fig. 3, from which it is seen that each groove comprises a horizontal portion 10 and a vertical portion or slot 11. In each of these grooves operates a guide plate 12 60 conveniently formed of a single piece of sheet metal bent into substantially T-shaped form. The horizontal portion 13 of each guide plate operates in the horizontal portion 10 of the associated groove, and the vertical or web portion 14 of each guide plate extends through the vertical slot 11 of the groove 8. The upper ends of the legs 15 are pivotally connected to the guide plates 12 by pivot pins 16. The legs 15 are 70 firmly braced by means of transverse bars or strips 17. A pair of links 18 is at one end pivoted to the legs 6 at the points 19 and at the other end to the pivot pins 16. A second pair of links 20 is at one end connected to the pivot pins 5 and at the other end to the legs 15 at the points 21. 75

When the legs are in supporting position, the guide plates 12 rest against the ends 9 of the groove 8, as shown in Fig. 1. 80 In this position the two pairs of legs diverge downwardly and form a firm support for the table top. To fold the legs it is only necessary to grasp one of the legs 15 near their upper end to slide the guide plates 12 85 toward the open end of the grooves. When this is done the links 18 are drawn forwardly and cause the legs 6 to rock toward the table top about the pivot pins 5. At the same time that the legs 15 are given a sliding motion through the guide plates 12, these legs also receive a pivotal movement about the points 21 through the links 20. By means of this exceedingly simple arrangement, both pairs of legs are moved 90 into folded position by a single operation. The legs 16 are spread so as to permit the legs 15 to fold directly against the under surface of the table, as shown in Fig. 2. The links 18 and 20 do not interfere in the least with the folding of both pairs of legs flat 100 against the under side of the table. When the table is in this folded position it occupies very little space and may be stored away in a place where but little room is 105 available. The form of the grooves 8 and the guide plates 12 allows the latter to slide freely in the grooves and at the same time positively prevents separation of the guide plates from the grooves. 110

Having thus described my invention what I claim as new and desire to secure by Letters Patent of the United States is:

1. A folding table, comprising a top provided on its under surface with grooves running from one end toward a point near the center, integral bearing flanges slidably mounted in said grooves, a second pair of legs pivotally connected to said bearing flanges, said grooves having their inner limits at such a point that the upper ends of the legs, limited in their inward movement thereby, will incline toward each other when the table is erected, a second pair of legs pivotally connected to said top near the end opposite said grooves, diagonally arranged links between the two pairs of legs for the purpose of folding said legs under the table top by a single operation, and said links being each pivoted at one end to the pivotal axis of the legs to facilitate the folding of said legs in the shortest space possible.
2. A folding table, comprising a top provided with T-shaped grooves on its under surface running from one end toward a point near the center of said top, bearing flanges slidably mounted in said grooves, a

pair of legs pivotally connected to said bearing flanges, said grooves having their inner limits at such a point that the upper ends of the legs, limited in their inward movement thereby, will incline toward each other when the table is erected, a second pair of legs spaced a farther distance apart than said first mentioned legs and pivotally connected to said table top near the end opposite said grooves, diagonally arranged links between the two pairs of legs, said links being each pivoted at one end to the outside of said first mentioned legs and at the other end to the inside of said widely spaced legs to thereby permit said legs to fold closely against the under surface of said table top, and said links being each pivoted at one end to the pivotal axis of the legs to facilitate the folding of said legs in the shortest space possible.

In witness whereof, I hereunto subscribe my name this 2nd day of May A. D. 1911.

CHARLES WILLIAM DUNKELBURGER.
